DOORKNOB CONSTRUCTION

Samuel J. Cronin, New York, N. Y.

Application January 12, 1950, Serial No. 138,176

4 Claims. (Cl. 292—348)

1

This invention relates to a replaceable door knob construction.

It is an object of the present invention to provide a door knob construction wherein the knob element itself can be readily replaced with other knobs and wherein, when such knob is connected to its holder element, it is cushioned therein so that it will not be easily broken inasmuch as such knobs will be made of fragile glass or porcelain and so that any blow upon the handle or knob will be cushioned.

It is another object of the present invention to provide a replaceable door knob construction wherein the only part which is replaced is the knob element itself and wherein thereafter the new knob can be made secure with the same parts whereby to make a replaceable door knob construction which makes possible the replacement of the knob without great expense and wherein the knobs can be changed easily and frequently when a different color scheme or design of the knob is desired.

Other objects of the present invention are to provide a door knob construction which is simple, inexpensive to manufacture, has a minimum number of parts, compact, consumes little space, durable, shock-proof, wherein the knob element itself is floatingly mounted in the attaching parts, permits a quick change of the knob elements and efficient in operation.

For other objects and for a better understanding of the invention, reference may be had to the following detailed description taken in connection with the accompanying drawing, in which

Fig. 1 is a fragmentary perspective view of the door knob construction embodying the features of the present invention.

Fig. 2 is a collective and sectional view of the door knob parts.

Fig. 3 is a transverse sectional view taken on line 3—3 of Fig. 1.

Fig. 4 is a spring ring used for the assembly of the knob element in the body element.

Fig. 5 is a perspective view of a rubber cushioning ring.

Fig. 6 is a sectional view of the resilient driving pin units connected between the knob element and the body element.

Referring now to the figures, 10 represents a door having the usual latch assembly 11 in the edge thereof. Latch element 12 can be turned by knob shaft 13. A latch element 14 can be turned by a key extending through a key opening 15 of a plate 16 on the door face.

A body element 17 is fixed to the shaft by a

set screw 18. This body element 17 is recessed on its front face to receive flanged end 19 of a knob element 21. In the bottom of the recessed end of the body element 17 are three holes 22 spaced one hundred twenty degrees apart and adapted to receive resilient driving pins 23. The flanged end 19 of the knob element 21 is similarly provided with openings 24 for receiving the resilient pins 23. Each resilient pin comprises a rubber sleeve 25 and an internal coil spring 26, Fig. 6.

With the flanged end 19 in place in the recessed end of the body 17, a rubber ring 27 is fitted in the recess over the flanged end and a spring retaining ring is disposed and seated in a peripheral groove 29 in the open end of the body and over the rubber ring 27 and flange 19 whereby to lock and retain the knob element 21 in the body 17. The knob element 21 is accordingly floatingly mounted within the body and will withstand shock. The driving pins 23 are sufficiently rigid so as to effect a good driving connection between the knob and body elements. The body element 17 has a central hole 31 for receiving the shaft 13. The knob 21 is formed of glass, porcelain, or other fragile material. It is hollow and has a large opening in the flanged end, as indicated at 32, for receiving the shaft 13. The diameter of this hole is greater than the shaft 13 so that at no time can the flanged end or the fragile material of the knob element engage or be destroyed by the shaft 13. The knob element 21 can receive a blow, but the resilient elements will cushion this blow to prevent breakage of the fragile knob element 21. The turning of the knob element will turn the body 17 and shaft 13 due to its connection by means of resilient driving pins 23 which extend between the elements. The diameter of the flange is slightly less than the internal diameter of the recessed end of the body 17. The knob element is accordingly floatingly connected with the body element 17. There is little opportunity for destruction of the knob element.

It will be apparent that at any time it is desired to change the knob elements for a different pattern or color, that the spring retaining ring 28 can be easily removed from the groove 29 of the body 17 and the flanged end of the knob element withdrawn from the body 17. A new knob element can be reinserted and retained in the body 17 by fitting the rubber ring 27 thereover and snapping the retaining ring 28 in place within the groove 29.

Holes 34 and 35 are provided upon the ends of the spring ring 28 and are adapted to receive a

tool which will draw the ends of the ring together so as to permit the insertion of the ring into the recess 29 or the withdrawal of the same from such recess. The ring 28 is of the snap ring type and will be snapped in and out of the groove 29. 5

It will be apparent that the knob element can be made of any other material such as plastic or even metal and the same floating means can be used for the connection of the knob to the body.

It will also be apparent that the knob element and the body element can be made differently so that the flange may be provided upon the body element and the recess provided upon the knob element and still the resilient connection, as above described, can be effected. The opening in the body element can be either round or square, as may be desired. The set screw 18 will prevent the axial displacement of the body element from the shaft 13.

It will also be apparent that at all times the 20 knob element will be protected from any knock or blow.

While various changes may be made in the detail construction, it shall be understood that such changes shall be within the spirit and scope 25 of the present invention as defined by the appended claims.

I claim:

1. A door knob construction comprising a shaft, a body connected to the shaft, said body 30 having a recessed end, a replaceable door knob element having a flanged end adapted to seat in the recessed end of the body, a cushioning ring surrounding the flanged end of the knob, a retaining ring surrounding the cushioning ring 35 and connected to the body and driving connection means extending between the flanged end of the knob and the body.

2. A door knob construction comprising a shaft, a body connected to the shaft, said body 40 having a recessed end, a replaceable door knob element having a flanged end adapted to seat in the recessed end of the body, a cushioning ring surrounding the flanged end of the knob, a retaining ring surrounding the cushioning ring 45 and connected to the body and driving connection means extending between the flanged end of

the knob and the body, said driving end connection means comprising a plurality of angularly spaced pin assemblies, each of the pin assemblies comprising a rubber sleeve with a coil spring disposed in the center thereof.

3. A door knob construction comprising a shaft, a body element connected to the shaft, a knob element adapted to be replaceably connected upon the body element, one of said elements having a recess and the other of said elements having an enlargement adapted to fit the recess of the one element, a cushioning ring surrounding the enlargement end of the other element, a retaining ring surrounding the cushioning ring and connected to the one element and driving means drivingly connecting the knob element with the body element.

4. A door knob construction comprising a shaft, a body element connected to the shaft, a knob element adapted to be replaceably connected upon the body element, one of said elements having a recess and the other of said elements having an enlargement adapted to fit the recess of the one element, means for securing the elements together, and resilient driving means drivingly connecting the knob element with the body element, and said resilient driving means comprising a plurality of angularly spaced pin assemblies, each of the pin assemblies including a rubber sleeve with a coil spring disposed in the center thereof, said elements having openings registerable with one another for receiving the pin assembly.
